(57) **CLAIM**

The ornamental design for cutting elements for a chainsaw chain as shown and described.

DESCRIPTION

FIG. 1 is a perspective view of the claimed design of cutting elements for a chainsaw chain, according to a first embodiment;

FIG. 2 is a front view of the claimed design of FIG. 1;
FIG. 3 is a rear view of the claimed design of FIG. 1;
FIG. 4 is a top view of the claimed design of FIG. 1;
FIG. 5 is a bottom view of the claimed design of FIG. 1;
FIG. 6 is a right end view of the claimed design of FIG. 1;
FIG. 7 is a left end view of the claimed design of FIG. 1;
FIG. 8 is a perspective view of the claimed design of cutting elements for a chainsaw chain, according to a second embodiment;

FIG. 9 is a front view of the claimed design of FIG. 8;
FIG. 10 is a rear view of the claimed design of FIG. 8;
FIG. 11 is a top view of the claimed design of FIG. 8;
FIG. 12 is a bottom view of the claimed design of FIG. 8;
FIG. 13 is a right end view of the claimed design of FIG. 8;
FIG. 14 is a left end view of the claimed design of FIG. 8;
FIG. 15 is a perspective view of the claimed design of cutting elements for a chainsaw chain, according to a third embodiment;

FIG. 16 is a front view of the claimed design of FIG. 15;
FIG. 17 is a rear view of the claimed design of FIG. 15;
FIG. 18 is a top view of the claimed design of FIG. 15;
FIG. 19 is a bottom view of the claimed design of FIG. 15;
FIG. 20 is a right end view of the claimed design of FIG. 15;
and,

FIG. 21 is a left end view of the claimed design of FIG. 15.
The ornamental design which is claimed is shown in solid lines in the drawings. The broken lines in the drawings are for illustrative purposes only and form no part of the claimed design. Broken lines formed by substantially equal length dashes show unclaimed subject matter.
